CLAIM

The ornamental design for a wearable fan, as shown and described.

DESCRIPTION

FIG. 1 is a perspective view of an embodiment of a wearable fan, in accordance with the design;

FIG. 2 is a front view of the wearable fan of FIG. 1;

FIG. 3 is a top view of the wearable fan of FIG. 1;

FIG. 4 is a bottom view of the wearable fan of FIG. 1;

FIG. 5 is a rear view of the wearable fan of FIG. 1;

FIG. 6 is a right-side view of the wearable fan of FIG. 1;

FIG. 7 is a left-side view of the wearable fan of FIG. 1;

FIG. 8 is a perspective view of an alternative embodiment of a wearable fan, in accordance with the design;

FIG. 9 is a front view of the wearable fan of FIG. 8;

FIG. 10 is a top view of the wearable fan of FIG. 8;

FIG. 11 is a bottom view of the wearable fan of FIG. 8;

FIG. 12 is a rear view of the wearable fan of FIG. 8;

FIG. 13 is a right-side view of the wearable fan of FIG. 8; and,

FIG. 14 is a left-side view of the wearable fan of FIG. 8. The broken lines illustrate portions of the wearable fan that form no part of the claimed design.
